4 Sheets-Sheet 4

UNITED STATES PATENT OFFICE.

LESTER KYLE ALDRICH, OF SIDNEY, OHIO.

DELIVERY FOR FOLDING MACHINES.

Application filed August 31, 1925. Serial No. 53,594.

The invention relates to improvements in deliveries for folding machines.

The object of the present invention is to improve the construction of deliveries for folding machines and to provide simple, practical and efficient means for receiving and packing folded sheets which will be capable of ready adjustment to accommodate folded sheets of different size folds.

10 A further object of the invention is to provide a delivery mechanism of this character equipped with means for driving the sheet with a positive motion until it reaches the delivery board thereby eliminating any 15 drop of the sheet by gravity in traveling from the folding rolls to the delivery board, as dropping a sheet by gravity is always uncertain and almost physically impossible in the case of heavy stock such as rough paper 20 and three ply tag board. It will readily be seen that a machine sufficiently large to handle ten inch pages, operating on three inch pages would require a seven inch drop by gravity of such three inch pages in order 25 for the latter to reach the delivery board from the folding rolls. The result would be a clogged delivery as small pages are springy and tend to open up in passing down the chute and friction of the sheets against the 30 chute soon overcomes the weight of the folded sheets and the latter fails to reach the delivery board. This objection is obviated in the present invention by the provision of means for raising and lowering the delivery 35 board to eliminate the extra drop.

It is also an object of the invention to effect this raising and lowering of the delivery board without the necessity of any adjustment of the folding machine and to permit 40 the delivery board to be raised and lowered while the folding machine is in operation.

Another object of the invention is to enable the packer head to be adjusted laterally without the addition or removal of any parts 45 so that the packer head will operate properly with any adjustment of the delivery board and the chute which guides the paper from the folding rolls to the delivery board.

Another object of the invention is to provide an adjustable delivery adapted for use 50 in machines having various types and arrangements of folding mechanism whether the same be either for parallel folding or square folding.

55 With these and other objects in view, the

invention consists in the construction and novel combination and arrangement of parts hereinafter fully described illustrated in the accompanying drawings and pointed out in the claims hereto appended, it being understood that various changes in the form, proportion and minor details of construction, within the scope of the claims, may be resorted to without departing from the spirit or sacrificing any of the advantages of the 65 invention.

In the drawings:

Figure 1 is a side view of a delivery constructed in accordance with this invention.

Fig. 2 is a plan view of the same partly 70 in section.

Fig. 3 is a detail elevation of the packer head.

Fig. 4 is a vertical sectional view illustrating the arrangement of the roll gears 75 the folding rolls of the upper portions of the chutes being shown in elevation.

Figs. 5 and 6 are detail views of the adjustable deflector bar.

Fig. 7 is a plan view partly in section 80 illustrating the arrangement of a double delivery for use where the delivery is desired on both sides of a machine.

Fig. 8 is a detail side view of the upper portion of one of the double chutes.

In the accompanying drawings in which is illustrated the preferred embodiment of the invention the delivery comprises in its construction a pair of vertically disposed chutes 1 located beneath and extending from the 90 folding rolls hereinafter described to the delivery board 2 for guiding the folded sheets of paper from the folded rolls to the delivery board. The vertical chutes 1 are provided with grooves or channels 3 to receive the folded sheets as clearly illustrated in Fig. 2 of the drawings and they are composed of spaced parallel sides or flanges and a connecting web or flange forming a channel chute. The chutes are provided at their upper portions with annular bosses 4 having sockets or openings for the reception of the inner ends of horizontal laterally extending supporting arms 5 consisting of rods secured at their inner ends by clamping screws 6 or other suitable fastening devices in the openings or sockets of the bosses 4 and extending outwardly from the chutes and slidably mounted in openings 7 of the frame of the machine and secured in their 105 110

adjustment by clamping screws 8. The slide-
able adjustment of the arms 5 of the chutes
will enable the latter to be moved inwardly
and outwardly with respect to each other to
space the chutes the proper distance apart
to suit the size of the folded sheets. The
chutes are provided with vertical abutments
9 consisting of preferably reversely arranged
channel portions formed by a flange 10
spaced from and arranged in parallelism
with the sides of the chute and connected
with the same by a web or flange. The abut-
ment 9 may be constructed in any other
desired manner as will be readily understood
and it presents a paper engaging face 11
against which the sheets are packed when
the said sheets after descending the chute
and reaching the delivery board are flipped
out of the said chutes by a packer head 12.
The delivery board is suitably secured to
and supported by transverse strips 13 of
steel of other suitable material which extend
across the lower face of the delivery board
and are secured at their ends upon vertically
slidable shoes 14 located beneath the delivery
board at opposite sides thereof and provided
at their upper and lower portions with
spaced projecting lugs 15 arranged in pairs
and forming ways for vertical guide bars
16. The vertical guide bars 16 which are
constructed of suitable metal are bolted or
otherwise secured to the frame of the
machine and they form guides or rolls on which
the shoes slide in raising and lowering the
delivery board and the said guide bars 16
are provided with a series of holes 17 ar-
ranged at intervals of the desired distance
and adapted to receive removable plugs 18
which also engage the shoes. The remov-
able plugs 18 consist of headed pins and
are adapted to be arranged in any of the
holes 17 of the vertical guide bars and they
extend inwardly beyond the guide bars and
their inner ends fit in suitable sockets or
holes 19 in the shoes.

The delivery board is equipped with verti-
cal laterally adjustable sides 20 and it has
a fixed central extension 21 located at the
inner end of the delivery board and extend-
ing therefrom to a point between the chutes
and it is adapted to form a stop and support
for the folded sheets passing down the chute.
The adjustable sides 20 are provided with
laterally extending arms 22 slidably mount-
ed in openings 23 in brackets 24 which are
secured to the upper face of the delivery
board at the inner end thereof. The arms
22 which preferably consist of rods are se-
cured at their inner ends in openings or
sockets 25 of metallic plates 26 which are
arranged at the outer face of the sides 20
of the delivery board and suitably secured
to the same. The brackets 23 are provided
with winged clamping screws 27 which en-
gage the arms 22 and secure the sides 20 of

the delivery board in their lateral adjust-
ment. The inner ends of the adjustable
sides 20 are equipped with flanged extensions
28 consisting of plates of substantially the
length of the central extension 21 and pro-
vided at their outer edges with vertical at-
taching flanges 29 which are suitably secured
to the outer faces of the adjustable sides
20 of the delivery board. The flanged ex-
tensions 28 are provided with outer portions
conforming to the configuration of and slid-
ably interlocked with the chutes and adapted
to brace the same at the lower portions
thereof and maintain the chutes in the proper
vertical position. The said extensions 28 are
provided with rectangular recesses 30 to re-
ceive the abutments 9 of the chutes and are
provided with lateral extensions 31 formed
by the recesses 30 and end recesses 32 and
fitting in the channels of the chutes. This
construction also permits of the vertical ad-
justment of the delivery board and the side
extensions thereof without the chutes inter-
fering with such adjustment. The central
and side extensions of the delivery board
form ample supports for the folded sheets
for maintaining the same in position to be
operated on by the packer head and for also
supporting the folded sheets after they have
been operated on by the packer head.

The packer head 12 is provided with fixed
and adjustable upwardly extending fingers
33 and 34 and it has spaced centrally ar-
ranged guide openings 35 located at the bot-
tom of the packer head and slidably receiv-
ing the horizontal shafts 36 upon which the
packer head slides. The fixed centrally ar-
ranged fingers 33 consist of vertical rods
which are mounted at their lower ends in
suitable sockets 37 of the packer head and
the adjustable fingers 34 extending through
longitudinal slots 38 in the packer head and
are provided below the latter with laterally
extending horizontal arms 39 which extend
through openings 40 in blocks 41 depending
from the lower face of the packer head at
the ends thereof. The blocks 41 are prefer-
ably provided with upwardly extending
stems 42 which are secured in suitable open-
ings 43 in the packer head by means of
clamping screws 44. The blocks are pro-
vided with winged clamping screws 44 which
engage the horizontal arms 39 of the fingers
34. The slots 38 extend longitudinally of
the side portions of the packer head and the
fingers 34 which preferably consist of square
rods are adapted to be moved inwardly and
outwardly in the slots 38 and they are
secured in their adjustment by the said
clamping screws 45. The central fingers 33
are detachably secured in the sockets 37 by
means of suitable clamping screws 46. The
packer head operates in the usual manner
and reciprocates along the fixed shafts 36
and is adapted to operate in the usual man-

ner. The fingers of the packer head operate in the spaces at opposite sides of the central extension between the same and the side extension and they flip the folded sheets 5 from the channels of the chutes and carry the sheets past the abutments 9 whereby the folded sheets are packed on the delivery board.

In Fig. 1 of the drawing the delivery is 10 illustrated in connection with two sets of folding rolls. The pair of upper rolls 47 and 48 are second folding rolls and are adapted to receive a sheet 49 of paper which is carried between the second folding rolls 15 47 and 48 by the knife 50 which is adapted to make a square fold in the usual manner. The folded sheet of paper 49 passing downwardly between the folding rolls 47 and 48 is directed by a deflector bar 51 to a set of 20 folding rolls 52, 53 and 54 or to tape pulleys 55. The deflector bar 51 is also adapted to be adjusted for permitting the folded sheet to pass downwardly directly between the roll 53 and the pulleys 55 into the upper 25 end of the chutes without further folding of the sheets. The deflector bar 51 consists of a flat bar provided at its ends with apertured lugs 56 in which are secured pivots or journals 57 and 58. The pivots or journals 30 57 and 58 are secured in the lugs 56 by clamping screws 59 and they are journaled in suitable bearings in the frame of the machine and the journal 58 is extended and is designed to be equipped with operating 35 mechanism for adjusting the deflector bar and for securing the same in its adjustment. Any suitable means may be employed for this purpose as will be readily understood. The deflector bar 51 is arranged in the 40 inclined position illustrated in full lines in Fig. 1 of the drawings for directing the folded sheet 49 to the set of folding rolls 52, 53 and 54 and it is also adapted to be arranged in the oppositely inclined dotted 45 position illustrated in Fig. 1 of the drawing for directing the folded sheet to the tape pulleys 55 and it is arranged in the vertical dotted line position shown in the said figure to permit the folded sheet to pass downwardly without further folding to the roll 53 and the pulleys 55 which feed the folded sheet to the chutes. The tape pulley 55 carries an endless tape 60 and when the folded sheets are directed by the deflector bar to the 50 right in Fig. 1 of the drawings on to the pulleys and the tapes the sheets are operated on by a third fold knife 61 which forms a third fold in the folded sheet and carries the same between the third fold rolls 62. The 55 third fold knife 61 and the folding rolls 62 operate in the usual manner and the folded sheets from the roll 62 are taken care of by a delivery separate from the delivery shown and described in the present application.

60 The set of rolls 52, 53 and 54 are arranged

with their axis disposed substantially in the form of a right angle in the usual manner and cooperate with guide plates 63 and 64 for making a parallel fold. The folded sheet from the second folding rolls is directed by the deflector bar between the rolls 52 and 53 and the sheet is fed between the guide plates 63 and 64 and when it engages the fingers 65 and adjustable stop 66 the folded sheet is buckled and forced downwardly between the rolls 53 and 54 where the parallel fold is completed and the folded sheet fed into the chutes. The upper ends of the sides of the chutes are beveled at their inner sides to form a flaring mouth or entrance 67.

The pair of folding rolls 47 and 48 always rotate in the same direction and motion is communicated from the roll 48 to the set of rolls 52, 53 and 54 and to the pulley 55 85 through an intermediate interchangeable gear 68 which rotates the set of rolls 52, 53 and 54 and the pulley 55 in the direction of the arrows in Fig. 1 of the drawings and when the rolls rotate in the direction of the 90 arrows the deflector bar is adapted to be arranged in the inclined position shown in full lines in Fig. 1 and also in the inclined position shown in dotted lines in the said figure either for making a parallel fold or for 95 directing the folded sheet to the mechanism of the third fold knife 61 and the folded rolls 62 for making an angular fold. When, however, it is desired to direct the folded sheet to the chute without making a third 100 fold, the intermediate interchangeable gear 68 is removed and an intermediate gear 69 is arranged for transmitting motion from the roll 48 to the pulley 55 and to the set of rolls 52, 53 and 54. This will reverse the rotation 105 of the pulley 55 and the set of rolls 52, 53 and 54. The adjacent peripheral portions of the roll 53 and the pulley 55 will move downwardly and feed the folded sheet into the chute without making the third fold.

For convenience of illustration the intermediate interchangeable gears 68 and 69 are indicated in Fig. 1 of the drawings one of the intermediate gears 68 being indicated in full lines and the other gear 69 being indicated in dotted lines. It will be understood that of course, only one of these gears is to be used at a time. The second set of folding rolls which always rotate in the same direction are driven from the main shaft by a 115 miter gear 70 and each of the rolls 47 and 48 is provided with a gear 71. The gear 71 of the rolls 47 and 48 are arranged within the frame as clearly illustrated at the right hand end of Fig. 6 of the drawings and the set of rolls 52, 53 and 54 are connected by gears 72, 73 and 74 which mesh and cause the said set of rolls to rotate in unison. The gearing for transmitting motion from the upper roll 48 to the set of rolls 52, 53 and 54 or to the 120 125 130

5 pulley 55 is located exteriorly of the frame as illustrated at the left hand side of Fig. 6 of the drawings. The roll 53 is provided at its journal 75 with a gear 76 with which the 10 interchangeable gear 68 meshes as illustrated in Fig. 6 of the drawings. The gear 68 is detachably mounted on a stud 77 and is secured theron by means of a winged nut 78 mounted on the threaded outer end of the 15 stud 77. The stud 77 is suitably mounted at its inner end on the frame of the machine preferably in a threaded socket as shown but it may be secured to the frame in any other desired manner. The other intermediate 20 gear 69 when in use is mounted on a similar stud 79.

In Fig. 1 of the drawings, the folding machine is shown equipped with mechanism for making either a parallel or an angular fold 25 at the third fold. In folding machines equipped with means for making either a right hand or left hand parallel fold at the third fold the double delivery illustrated in Fig. 9 of the drawings is employed. The 30 double delivery is constructed substantially the same as that heretofore shown and described with the exception of the duplication of the delivery boards and the provision of an abutment at each side of each of the 35 chutes. The delivery boards 80 as shown in Fig. 9 are provided at their inner ends with central extensions 81 and they are equipped with adjustable sides 82 and 83. The sides are provided with laterally extending arms 84 which are adjustably mounted in brackets 85 constructed and arranged the same as those before described. The sides of the adjustable sides 83 of the 40 delivery board 81 terminate at the inner end of the body portion of the delivery board while the sides 82 of the delivery board 80 are equipped with flanged extensions 86 each consisting of a plate provided with a vertical flange 87 secured to the outer face of the inner end of the adjustable side 82. The horizontal portion of the plate of the extension 86 extends from a point adjacent the inner end of the delivery board 80 to a point adjacent the inner end of the 45 delivery board 81 and it is provided at its outer side with intermediate and terminal recesses 88 and 89 which feed a pair of abutments 90 and 91 located at opposite sides of each chute 92. The chute 92 is provided 50 with a laterally extending arm 93 which is slidably mounted similar to the arm of the chute heretofore described. The chute 92 is provided at its upper portion with a boss 94 in a socket of which the inner end of the 55 arm 93 is secured by means of winged clamping member 95. The abutments 91 and 92 are located at opposite sides of the channel 96 of the chute 92 and folded sheets of paper descending the chute is adapted to be flipped 60 past either of the abutments 90 and 91.

The flanged extension 86 is adapted to brace the chute 92 at the lower portion thereof similar to the flanged extension shown in Figs. 1 and 2 and the adjustment of the double delivery is substantially the same as 70 the adjustment of the single delivery. Should it be desired to set the single delivery for sheets four inches larger each way the thumb screws 27 which clamp the laterally extending arms 22 of the sides of the 75 delivery chute are loosened and the slides are moved outwardly towards the frame two inches and carry with them the chutes 1, the clamping screws 8 of which are loosened previous to such adjustment. The packer 80 head fingers 34 are then adjusted outwardly a distance of two inches each. The central fingers 33 being fixed do not require any adjustment. The delivery may be adjusted to accommodate folded sheets of any size within 85 the capacity of the machine and the adjustment may be made without stopping the machine and folded sheets will be positively fed down the chutes from the folding rolls to the delivery board without any gravity drop and there will be no liability of the folding machine clogging while operating on large or small sheets or stock of any character handled by the machine.

What is claimed is:

1. A delivery for folding machines including spaced vertical chutes arranged to receive folded sheets from the folding mechanism of the machine, a delivery board having spaced sides extending outwardly from the chutes, means for adjusting the chutes and the sides of the delivery board laterally to accommodate folded sheets of different sizes and means for simultaneously raising and lowering the delivery board and the adjustable sides thereof to enable the delivery board to be arranged so that the folded sheets of different sizes will be positively fed by the machine to the delivery board without a gravity drop in the chutes.

2. A delivery for folding machines including spaced vertical chutes having channels to receive the folded sheets, extensions carried by the delivery board and having laterally extending portions arranged in the channels of the chutes to support the folded sheets, a packer head having fingers operating between the said extensions and means for raising and lowering the delivery board so that the sheets may be positively fed by the machine to the delivery board without a gravity drop in the chutes.

3. A delivery for folding machines including spaced chutes provided with channels to receive the folded sheets, a delivery board having intermediate and side extensions extending between the chutes, the side extensions having portions arranged in the channels of the chutes, means for raising and lowering the delivery board to enable the

folded sheets to be positively fed to the same without a gravity drop in the chutes, a packer head having fingers operating between the extensions of the delivery board 5 and means for adjusting the chutes and the side extensions laterally to accommodate folded sheets of different sizes.

4. A delivery for folding machines including spaced chutes provided with channels to receive the folded sheets, a delivery board having intermediate and side extensions extending between the chutes, the side extensions having portions arranged in the channels of the chutes, means for raising 10 and lowering the delivery board to enable 15 the folded sheets to be positively fed to the same without a gravity drop in the chutes, a packer head having fingers operating between the extensions of the delivery board, 20 means for adjusting the chutes and the side extensions laterally to accommodate folded sheets of different sizes, and separate means for adjusting certain fingers of the packer head laterally to suit the adjustment of the 25 chute and side extensions.

5. A delivery for folding machines including spaced vertical chutes having channels to receive the folded sheets, a delivery board provided with laterally adjustable sides, side extensions carried by the adjustable sides and feeding the chutes and extending into the channels thereof laterally extending arms mounted on the chutes and on the sides of the delivery board, means for 30 engaging the arms for securing the sides and the chutes in lateral adjustment and means for raising and lowering the delivery board to arrange the same to suit folded sheets of different sizes to permit the same 35 to be positively fed to the delivery board without a drop by gravity in the sheets.

6. A delivery for folding machines including spaced chutes adapted to receive the folded sheets, a delivery board provided with 40 brackets, adjustable sides having laterally extending arms slidably mounted in the brackets, arms extending laterally from the chutes, means for adjustably mounting the arms of the chutes, angular extensions secured to the sides of the delivery board 45 slidably interlocked with the chute for bracing the same and to support the folded sheets and means for raising and lowering the delivery board to arrange the same to 50 suit the size of the sheets and enable the latter to be positively fed to the delivery board without a gravity drop in the chutes.

7. A delivery for folding machines including spaced chutes provided with channels to receive the folded sheets, said chutes being provided with abutments having paper receiving faces, spaced from the chutes, a delivery board having extensions feeding the chutes and the abutments thereof and means 55 for raising and lowering the delivery board

to enable the folded sheets to be positively fed to the extensions without a gravity drop in the chutes.

8. A delivery for folding machines including spaced chutes having channels to receive the folded sheets, a delivery board having portions extending between the chutes to receive the folded sheets, fixed vertical guides located at opposite sides of the delivery board, a pair of spaced shoes slidable upwardly and 70 downwardly on the guides and carrying the delivery board and rigidly connected with the same to hold the delivery board permanently in relatively fixed relation with the shoes and means for securing the shoes in 75 their adjustment.

9. A delivery for folding machines including spaced chutes having channels to receive the folded sheets, a delivery board having portions extending between the chutes to 80 receive the folded sheets, vertical guides located at opposite sides of the delivery board, shoes located at opposite sides of the delivery board and provided with ways receiving the vertical guides, means for securing the shoes 85 at different vertical adjustments on the guides and means for connecting the guides and for supporting the delivery board.

10. A delivery for folding machines including spaced chutes having channels to receive the folded sheets, a delivery board having portions extending between the chutes to receive the folded sheets, vertical guides located at opposite sides of the delivery board, shoes located at opposite sides of the delivery board and slidably receiving the vertical guides, spaced tie bars connecting the shoes at opposite sides of the vertical 95 guides and supporting the delivery board 100 and means for securing the shoes in vertical 105 adjustment on the guides.

11. A delivery for folding machines including spaced chutes having channels to receive the folded sheets, a delivery board having portions extending between the chutes 110 to receive the folded sheets, vertical guides located at opposite sides of the delivery board, shoes located at opposite sides of the delivery board and provided at their outer faces with spaced projections forming ways 115 to receive the vertical guides, means for connecting the shoes and for supporting the delivery board thereon and means for securing the shoes in vertical adjustment on the 120 guides.

12. A delivery for folding machines including spaced chutes having channels to receive the folded sheets, a delivery board having portions extending between the chutes to receive the folded sheets, vertical 125 guides provided at intervals with holes, shoes located at opposite sides of the delivery board and carrying the same and provided at their upper and lower portions with spaced projections forming ways to receive 130

the vertical guides and plugs located between the lugs and engaging the shoes and adapted to be engaged in any of the holes of the guides for securing the shoes in vertical adjustment.

13. A delivery for folding machines including spaced guides having channels to receive the folded sheets, a delivery board having spaced extensions extending between the chutes, means for raising and lowering the delivery board to permit the folded sheets to be positively fed to the said board without a gravity drop in the chutes and a packer head provided with central and side fingers operating between the extensions of the delivery board and means for adjusting the side fingers laterally of the head.

14. A delivery for folding machines including spaced guides having channels to receive the folded sheets, a delivery board having spaced extensions extending between the chutes, means for raising and lowering the delivery board to permit the folded sheets to be positively fed to the said board without a gravity drop in the chutes, a packer head provided with longitudinal slots, fingers extending through the slots and means for adjusting the fingers along the slots to vary the distance between the said fingers.

15. A delivery for folding machines including spaced guides having channels to receive the folded sheets, a delivery board having spaced extensions extending between the chutes, means for raising and lowering the delivery board to permit the folded sheets to be positively fed to the said board without a gravity drop in the chutes, a packer head provided with longitudinal slots, fingers extending through the slots and having arms located beneath the packer head and extending longitudinally thereof and clamping means carried by the packer head for engaging the arms of the said fingers.

16. A delivery for folding machines including spaced guides having channels to receive the folded sheets, a delivery board having spaced extensions extending between the chutes, means for raising and lowering the delivery board to permit the folded sheets to be positively fed to the said board without a gravity drop in the chutes, a packer head provided with longitudinal slots, fingers extending through the slots and having arms located beneath the packer head and extending longitudinally thereof, projections carried by the packer head and having openings receiving the arms and clamping devices mounted on the projections and engaging the arms of the fingers.

17. A delivery for folding machines including spaced guides having channels to receive the folded sheets, a delivery board

having spaced extensions extending between the chutes, means for raising and lowering the delivery board to permit the folded sheets to be positively fed to the said board without a gravity drop in the chutes, a packer head provided with longitudinal slots, fingers extending through the slots and having arms located beneath the packer head and extending longitudinally thereof, blocks having openings to receive the arms and provided with stems detachably secured in the packer head, clamping means mounted on the blocks for engaging the arms of the fingers.

18. A delivery for folding machines including spaced guides having channels to receive the folded sheets, a delivery board having spaced extensions extending between the chutes, means for raising and lowering the delivery board to permit the folded sheets to be positively fed to the said board without a gravity drop in the chutes, a packer head provided with longitudinal slots, central fingers mounted on the packer head between the slots, side fingers extending through the slots and provided at their lower ends with arms disposed longitudinally of the packer head and means for slidably receiving the arms and for securing the same in adjusted position.

19. A delivery for folding machines including spaced vertical chutes, a delivery board having central and side extensions projecting between the chutes, a packer head having fixed centrally arranged fingers operating at opposite sides of the central extension, side packer head fingers adjustably mounted on the packer head and movable toward and from the central fingers to vary the space between them and means for adjusting the chutes and the side extensions of the delivery board laterally.

20. A delivery for folding machines including spaced vertical chutes, a delivery board having an intermediate extension, sides carried by the delivery board and provided with extensions, said extensions projecting between the chutes, means mounted on the delivery board and connected with the sides for adjusting the same and the extensions thereof, lateral separate means for adjusting the chutes toward and from each other, a packer head provided with fingers adjustable on the packer head to vary the distance between them to correspond with the adjustment of the chutes and the sides of the delivery board and means for raising and lowering the delivery board to enable the folded sheets to be positively fed to the said delivery board without a gravity drop in the chutes.

In testimony whereof I affix my signature,

LESTER KYLE ALDRICH.
